UNITED STATES PATENT OFFICE.

HARRY W. FEHR, OF PHILADELPHIA, PENNSYLVANIA.

AUTOMOTIVE TOY.

Application filed December 3, 1923. Serial No. 678,093.

To all whom it may concern:

Be it known that I, HARRY W. FEHR, a citizen of the United States, and a resident of the city of Philadelphia, county of Philadelphia, and State of Pennsylvania, have invented certain new and useful Improvements in Automotive Toys, of which the following is a specification.

My invention relates to toys and particularly to those which are provided with a motor, spring or electric, for impelling the toy over a plane surface and more particularly to the providing of such a toy or device with means to cause the toy to change its course or direction whenever it encounters an obstruction.

The principal objects of my invention are to provide a power driven toy with means which will cause the toy to rebound and at the same time skid, often through an angle as great as 180°, when the toy collides squarely with a rigid object, and will cause the toy to slide around and clear a small rigid object, such as the leg of a chair or a table, when the toy strikes the same obliquely or not squarely.

A further object of my invention is to provide an automotive toy with a resilient device which will change the direction of the travel of the toy when it encounters an obstruction, will cause the toy to slide clear of the obstruction, enabling the toy to continue its travel until it strikes another object, whereupon the toy will again change its direction of travel, and move in the new direction, until it strikes an obstruction, when the operation is repeated, and so on until the motor contained in the toy is run down or exhausted.

A further object of my invention is to provide an automotive toy having wheels rotating on axes which are fixed with respect to each other, with a resilient member projecting forwardly of the toy to cause the toy to rebound and in rebounding to skid and change the direction of its travel after it collides squarely with a substantially rigid object.

My invention further comprehends mechanism, the frame or body of which may embody a variety of different forms of toys, such as automobiles, boats, cars, animal figures, or any other suitable forms.

The form of my invention hereinafter described comprises a toy provided with a

frame having spring driven rotary supports or wheels, and a resilient bumper or deflector, so bowed or shaped that its crest or most forwardly extending surface is disposed somewhat on one side of a vertical plane coincident with the longitudinal axis of the toy. Such plane will usually be substantially between the wheels on opposite sides of the toy.

My invention also includes all of the various novel features of construction and arrangements of parts hereinafter more definitely set forth in the specification and claims below.

In the accompanying drawing Fig. 1 is a plan view of an automotive toy conveniently embodying my invention.

Fig. 2 is a side elevational view of the device shown in Fig. 1 and having indicated thereon in dot-and-dash lines the body of an enclosed automobile, as illustrating the manner in which the mechanism may be made to resemble any particular or selected object.

Fig. 3 is a fragmentary plan view of the forward end of the toy provided with a slightly modified form of resilient bumper or deflector embodying my invention; and

Fig. 4 similarly shows a further modification of my invention.

In the drawings, the motor frame 1 is of any well-known form and type having a pair of front wheels 2, 2 and a pair of rear wheels 3, 3, the axis 4 of the front wheels and the axis 5 of the rear wheels being fixed with respect to each other and to the frame 1 so that the toy will travel normally in one direction only,—in a straight line, if the axes be parallel or in a circular path if the axes be slightly inclined to each other and the frame. The driving wheels 2, 2 are preferably rigidly mounted on the shaft 6 extending through the frame 1, but the other pair of wheels 3, 3, which may not be driving wheels, may be mounted to rotate freely on the shaft 7. The shaft 6 is provided with a pinion 8 which meshes with a gear 9 on shaft 10 which also carries a pinion 11 which meshes with a gear 12 rigidly secured to a shaft 13 to which is also rigidly secured a pinion 14 which meshes with a gear 15 on the spring or motor drum 16. This train of gearing may be disposed within the frame in any suitable manner. The shaft 17 on which is mounted the spring drum 16 may be a winding shaft which would be pro-

vided with a key 18 for winding the spring in the drum 16. The shaft 6 may also be provided with a gear 19 driving a pinion 20 rigid with the governor shaft 21 of any suitable governing mechanism 22.

The motor frame 1 may also comprise any form of toy, such for example as form 1' of an automobile, but it is to be understood that it may simulate a street car, a locomotive, a boat, or an animal, bird, fish or insect; in fact, almost anything that would be attractive or interesting as a toy.

The frame or body 1 is provided with a spring bumper or deflector 23, the foremost portion or crest 24 of which is rounded outwardly, is convex in shape, and is located on one side of a vertical plane coincident with the longitudinal axis 25 of the toy which is substantially midway between the 20 wheels on opposite sides of the toy.

The front portions 26 and 27 of said bumper on either side of said rounded or convex portion 24 are also preferably convex and curve smoothly rearwardly and laterally, extending laterally beyond any projecting part or portion of the frame or body 1. Thus, when there is a key 18 permanently protruding laterally from the toy, the portions 26 and 28 extend laterally at least as far as the end of the key. Similarly, if the body be made to simulate any object, such as an animal having projections on the sides thereof, the front of the bumper should extend laterally on that side as far or slightly farther than such projecting part or portion. The ends 28 and 29 of the lateral sides of the bumper are also preferably rounded and bent to form inwardly extending portions 30 and 31 which respectively terminate in integrally rearwardly extending ends 32 and 33 which may be rigidly secured to any suitable part of the toy, as to the side of the motor plate by screws or rivets 34 or in any other suitable manner.

In Fig. 1 the rearwardly extending end portions 32 and 33 are of different lengths and contribute to the unsymmetrical shape of the bumper. The extent and direction of the rebound of the toy after a collision, is somewhat variable, depending to a great extent upon the place of the forward portion of the bumper where the impact occurs. When the toy is impelled rapidly forwardly and squarely against an obstruction, such as a vertical wall indicated by the dot-and-dash lines 35 in Fig. 1 and in a direction normal thereto, the crest or most forwardly extending portion 24 will strike squarely against the wall, the bumper will be compressed and the toy will rebound from the wall, but by reason of the fact that the spring is unsymmetrical and that the point of impact is on one side of a vertical plane coincident with the longitudinal axis of the toy, the toy in rebounding will skid and turn through

a considerable angle, often as great as 180° and start off in a new direction under the power of the spring of the motor mechanism contained therein. If, however, the toy strikes the obstruction obliquely or at an 70 angle, as on one of the rearwardly extending convex sides 26, 27, then the toy may rebound somewhat, and skid a little, or it may then slide along the wall or may bump back and forth until it turns enough to travel 75 along the wall to collide with the next obstruction.

The bumper shown in Fig. 3 is exactly like that shown in Fig. 1 except that the length of the rearwardly extending end 33' 80 is equal to that of the end 32 and extends the same distance forwardly of the frame 1. In this its action is substantially the same as that of the device as shown in Fig. 1 except that it may not cause the toy to skid 85 or rebound through quite so great an angle because the spring approaches a little closer to a symmetrical shape.

When the forward part of the bumper of the toy strikes against some obstruction, such as the leg 36 of a table, the toy will rebound somewhat and will turn in rebounding away from the object and will push forward again against the object, the smooth convex surface of the portion 27 sliding over the surface of the obstruction 36 until the rounded end 29 slides past the obstruction 36. This makes it apparent why it is that the bumper should extend laterally farther than any projection on the side of the toy 100 because if the bumper did not extend as far as it does then, for instance, the key might catch upon the object and impede or prevent its further progress.

Fig. 4 shows a further modification of the invention in which one side or end only of the bumper 23'' is attached to the frame or body 1. In this construction the rearwardly extending front portion 26 between the crest 24 and the rounded end 28 is long while the other portion, 27', is short and close to the rounded end 29. In this modification the inwardly extending portion 31' is also short and the end 33'' is preferably bent inwardly so that the end cannot catch upon a stationary object but will permit the toy, after the end 29 of the bumper clears the same, to proceed under its own power until another obstacle is encountered. In this form of the device, when the crest 24 of the bumper 23'' strikes squarely against an obstacle and rebounds, the skid may be even greater than that shown in the other two previously described modifications, the resiliency of the springs being substantially 120 the same, but when it strikes an object at an angle, as for instance the leg 36 of a chair, the rearward slope of the portion 26 is somewhat faster or more rapid than that of the 125 two previously described constructions and 130

therefore the device will slide around an object with greater ease perhaps than in the other two modifications.

In all the embodiments of my invention, 5 when the crest strikes squarely against any object, the bumper is compressed and this causes the toy to rebound and skid through an angle sufficient to make it start in a new direction. When an object is encountered 10 at some other place in the crest, then the toy may rebound and skid or it may slide around the object in the manner above described, and afterwards travel under its own power in a new direction. In all of the 15 embodiments of my invention, the width of the bumper or deflector is so great that when the bumper clears an object, then the whole device will also clear the same and travel past it, and continue to move in a 20 substantially straight path until some new obstruction is encountered.

It is to be noted that change in the direction of the travel of the toy is not due to any changing of the positions of the axes 25 of the wheels with respect to each other or to the frame. The toy skids or slides laterally on its wheels when the surface of the bumper or deflector strikes and then slides past an object, or it rebounds and skids when the crest 24 strikes squarely 30 against a relatively rigid obstruction. It is probably by reason of the offset of the crest and the non-symmetrical shape of the bumper or deflector that the toy, upon squarely 35 encountering an obstruction, rebounds and skids laterally sufficiently to be diverted away from such obstruction irrespective of whether the obstacle presents a plane, curved or other surface.

40 I do not desire to limit my invention to the precise details of construction and arrangement hereinabove set forth, as it is obvious that various modifications may be made therein without departing from the essential features of the invention as defined 45 in the accompanying claims.

Having thus described my invention, what I claim and desire to protect by Letters Patent of the United States is:

50 1. In an automotive toy comprising a frame or body, two pairs of wheels mounted to rotate on axes fixed with respect to each other and to said body, and a motor mounted in said frame to propel said toy, the combination of a resilient spring secured to and projecting forwardly from said body, the foremost portion of said spring being on one side of a vertical longitudinal plane substantially midway between the wheels.

55 60 2. In an automotive toy comprising a frame or body, two pairs of wheels mounted to rotate on axes fixed with respect to each other and to said body, and a motor mounted

in said frame to propel said toy, the combination of a resilient spring having a convex front face secured to and projecting forwardly from said body, the foremost portion of said spring being at one side of a vertical longitudinal plane substantially midway between the wheels. 65 70

3. An automotive toy comprising a frame and a motor mounted in said frame to propel said toy, the combination of a resilient bumper and deflector extending forwardly therefrom, the foremost portion of said 75 bumper being rounded and located on one side of a vertical longitudinal plane coincident with the longitudinal axis of the toy, and the portions of said bumper on each side of said rounded portion being 80 smoothly curved rearwardly.

4. In an automotive toy comprising a frame or body, and a motor mounted in said frame to propel said toy, the combination of a resilient bumper and deflector extending forwardly from said body, the foremost portion of said bumper being rounded and located on one side of a vertical plane coincident with the longitudinal axis of the toy, and the portions of said bumper on 85 each side of said rounded portion being smoothly curved rearwardly and extending laterally farther from said plane than any part or portion of said body. 90

5. In an automotive toy comprising a 95 frame, two pairs of wheels mounted in said frame, a motor mounted in said frame to rotate one pair of said wheels to propel said toy, the combination of a resilient spring secured to and projecting forwardly 100 of said frame, the foremost portion of said spring being on one side of a vertical longitudinal plane substantially midway between the wheels.

6. In an automotive toy comprising a 105 frame and two pairs of wheels supporting said frame, a motor mounted in said frame for rotating the forward pair of wheels to propel said toy, the combination of a resilient spring secured to and projecting forwardly 110 from said frame, the foremost portion of said spring being on one side of a vertical longitudinal plane substantially midway between the wheels.

7. The combination with an automotive 115 toy, of a resilient bumper affording a projection disposed on one side of a vertical plane coincident with the longitudinal axis of the toy, and having the front portions on opposite sides of said projection smoothly 120 curved rearwardly and extending laterally beyond the opposite sides of said toy.

In witness whereof, I have hereunto set my hand this 19th day of November, 1923.

HARRY W. FEHR.
